WILLIAM H. KELLOGG, OF DU QUOIN, ILLINOIS.

Letters Patent No. 62,637, dated March 5, 1867.

IMPROVEMENT IN GATE LATCHES.

The Schedule referred to in these Letters Patent and making part of the same.

TO ALL WHOM IT MAY CONCERN:

Be it known that I, WILLIAM H. KELLOGG, of Du Quoin, in the county of Perry, and State of Illinois, have invented a new and useful Improvement in Gate Latches; and I do hereby declare that the following is a full, clear, and exact description thereof, which will enable others skilled in the art to make and use the same, reference being had to the accompanying drawings, forming part of this specification, in which—

Figure 1 is a side view of a closed gate with the latch in place.

Figure 2 is a cross-section in the line x x , fig. 1.

Figure 3 is a face view of the part of the latch in the gate.

Figure 4 is a face view of the corresponding part in the post.

Similar letters of reference indicate like parts.

This invention relates to a device for a self-closing latch to a gate, which will open either way, and may be opened very readily, being more especially adapted to small gates that are often passed, and require a convenient as well as a sure fastening.

A A represent the posts of a gate frame, and B B the gate, hung by the hinges a a , with a flat steel spring, b , which twists when the gate is opened, and which closes the gate immediately by resuming its normal position when relieved of pressure. The latch c is a small bar, which is fitted into and passes through the front side of the gate, and is pushed out by a bent spring, f , let into the gate frame B. The front end of the latch c , fig. 3, fits into a corresponding cavity or socket, e , fig. 4, in the gate post; and fastened to it is a double-incline centre piece, d , fig. 4, which is arranged to strike either face upon one or other of two friction-rollers, g g , let into the corners of the gate post A when the gate closes; and thus, by the sudden and forcible swing of the gate operated on by the spring b , throws the latch c back and passes over the roller, so that the latch flies into its socket e by the pressure of the spring f . For opening the gate I fasten on the inside of the latch c a double bent lever, h h , which is pivoted to one end of the latch at z . In the knees of the double bent lever h h , are set friction-rollers, k k , which bear upon the frame of the gate when the levers are pressed upon to open it, and when the gate closes itself and forces the latch back, as will be seen in fig. 2.

Having fully described my invention, what I claim as new, and desire to secure by Letters Patent, is—

1. I claim the gate latch c , in connection with the double bent lever h h , the friction-rollers k k and g g , and the springs f and b , combined, arranged, and operated substantially as and for the purposes herein described.

2. I claim also the latch c , in combination with the flat spring b , for swinging and closing a gate, substantially as herein described.

W. H. KELLOGG.
